E. GRAY

DUMP BUCKET AND BAILER

Filed July 30, 1927

Ellsworth Gray Inventor

By Jesse P. Stone

Attorney

UNITED STATES PATENT OFFICE.

ELLSWORTH GRAY, OF HOUSTON, TEXAS, ASSIGNOR TO GRAY TOOL COMPANY, OF HOUSTON, TEXAS, A CORPORATION OF TEXAS.

DUMP BUCKET AND BAILER.

Application filed July 30, 1927. Serial No. 209,543.

My invention relates to buckets for use in deep well operations, particularly oil wells.

In cementing wells it is common to place the cement in a bucket of some length and let the bucket down in the well to a position closely adjacent the bottom of the well and there releasing the cement and withdrawing the bucket. There is some difficulty in carrying out this operation due to the fact that the valve will not remain open properly while the full charge of cement is discharged.

It is an object of my invention to provide a controlling device for the discharge opening of the bucket which will effectively close the lower end of the bucket while the cement is being lowered into the well and which will open and remain fixed in open position so as to assure the full discharge of the contents when the bucket is withdrawn. The invention resides particularly in the construction of the closing device whereby the valve is raised and held effectively out of its seat and in such position that it will not interfere with the discharge of the cement.

Referring to the drawing herewith for a fuller understanding of the invention, Fig. 1 is a side view illustrating my bucket in position in a well, the casing and the lower portion of the bucket being shown in central vertical section. Fig. 2 is a side elevation of the valve controlling member; and Fig. 3 is a section through the lower end of the cement bucket with my invention therein, the valve being in closed position. Like numerals of reference are employed to designate like parts in all the views.

My device is adapted for use in a well and in the drawing I have shown a casing 1 as indicating the walls of the well in which the cement is to be set. Said casing is shown as resting upon the lower end of the well 2, thus enclosing a cylindrical well bore extending upwardly to the surface and having the casing 1 therein.

The cement which is lowered to the bottom of the well, when cementing is necessary, is preferably an elongated pipe or tube 3 open at its upper end and provided with a bail or handle 4 by means of which it can be connected by a cable 5 or other supporting means to a hoisting means at the surface.

The lower end of the bucket is formed by a tubular housing or shoe 6. This hous-

ing has a threaded engagement at 7 with the main body of the bucket. The lower end of the shoe is provided with a flaring or bell-shaped opening 9, through which the cement is discharged. The upper end of the shoe 60 is also beveled or flared at 10 to form a seat for a valve 11.

The valve 11 is shown as a disc-shaped valve, the lower side of which is tapered to fit the seat 10. The disc has on its lower 65 side a downwardly extending eyelet or staple 12 by means of which the valve may be attached to a yoke or clevis 13 at the upper end of a valve stem 14. This connection, as will be noted, is a loose one allowing the 70 valve to swing to one side or the other of the valve stem, as shown particularly in Fig. 1, so as not to interfere with the passage of the cement when the valve is in open position.

The valve is opened by means of the valve stem which projects downwardly through the housing 6 and has at its lower end a foot or stop member 15 which is adapted to contact with the bottom of the hole when the 80 bucket is lowered and to thus force the valve upwardly off its seat. The valve is adapted to be held in raised position off its seat by means of resiliently hooked arms 17 connected to the valve stem at 18 adjacent the 85 lower end thereof. These arms are inclined outwardly and upwardly from their point of attachment and the outer ends are hooked downwardly at 20 to engage within an inner groove 19 in the inner wall of the housing. 90 As will be seen particularly from Fig. 3, the groove 19 is an annular one extending around the housing, the lower wall of the groove being undercut to provide an outwardly inclined shoulder 21 over which the 95 hooked ends 20 of the arms may engage.

It is to be noted that the arms 17 upon the valve stem bear against the lower flared opening 9 of the housing when the valve is in closed position, as indicated in Fig. 3. 100 The force of the arms 17 is not sufficient to hold the valve rigidly in its seat but is sufficient to hold it in place while the cement is being poured into the bucket and after the cement is thus poured above the valve, 105 the valve will be held in tightly closed position while the bucket is lowered to the bottom of the well. The contact of the foot 15 with the bottom of the well will throw the valve stem and the valve upwardly, bringing 110

2

the resilient arms 17 into the groove 19, where they will engage to prevent downward movement of the valve thereafter. When the valve has been thrown from its seat in this manner, its loose engagement with the valve rod will allow it to fall to one side, as shown in Fig. 1, and the full charge of cement may drain out of the bucket into the bottom of the well as the bucket is withdrawn. When the bucket has reached the surface the resilient arms 17 may be pressed inwardly so as to disengage them from the shoulder 21 of the groove and valve stem may be drawn back into the position shown in Fig. 3, closing the valve to receive another charge of cement.

While I have described the invention as adapted particularly for discharging cement, it is to be understood that it may be used to discharge water into a well in the standard rig system of drilling or for any similar purpose. I do not wish to be limited, therefore, to any particular use of my invention.

25 Having thus described my invention, what I claim as new is:

1. In a device of the character described, a bucket open at its lower end, a valve seat in said bucket, a valve stem, a valve free to move upwardly away from said seat, except for a loosely pivoted connection between said valve and the upper end of said stem, said stem projecting from said bucket to contact with the bottom of the well and

raise said valve upwardly away from said seat.

2. In a device of the character described, a bucket open at its lower end, a valve in said bucket, a valve stem, a loosely pivoted connection between said valve and the upper end of said stem, said stem projecting from said bucket to contact with the bottom of the well and raise said valve, and means on said valve stem engaging said bucket to prevent downward movement of said valve after it has been properly unseated.

3. In a device of the character described, a bucket open at its lower end, a valve in said bucket, a valve stem, a loosely pivoted connection between said valve and the upper end of said stem, said stem projecting from said bucket to contact with the bottom of the well and raise said valve, and resilient hooks on said stem engaging said bucket when said valve is raised for the purpose described.

4. A bucket for cement and the like comprising a tubular body open at both ends, a housing in the lower end having a valve seat therein, a valve in said seat, a valve stem, means linking said stem loosely to said valve, said stem adapted to project below said bucket, and means to retain said valve in open position after it has been raised from its seat in use.

In testimony whereof I hereunto affix my signature this 23d day of July, A. D. 1927.

ELLSWORTH GRAY.
